DROP BRAKE

Filed Dec. 10, 1925

Patented Mar. 12, 1929.

1,705,304

UNITED STATES PATENT OFFICE.

CHARLES J. NASH AND JACK WILSON, OF CHICAGO, ILLINOIS, ASSIGNORS TO UNIVERSAL DRAFT GEAR ATTACHMENT CO., A CORPORATION OF ILLINOIS.

DROP BRAKE.

Application filed December 10, 1925. Serial No. 74,466.

This invention relates to railway brakes, and more particularly to the winding mechanism thereof.

One of the objects of the invention is the provision of a new and improved mechanism for holding a drop brake staff in elevated position.

Another object of the invention is the provision of new and improved means whereby a brake staff may be raised and lowered, together with new and improved means for automatically securing said staff in adjusted position when the same is elevated.

15 A further object of the invention is the provision of a new and improved brake wheel or lever and means for securing the same to the upper end of the brake staff, together with means for permitting the 20 upper surface of the wheel to lie flush with the floor or upper surface of the car.

A still further object of the invention is the provision of a new and improved drop brake staff and associated mechanism that is 25 cheap to manufacture, easily assembled, efficient in operation, composed of a minimum number of moving parts, that is not likely to become broken or get out of order, and one in which the staff may be raised or 30 lowered with a minimum amount of time and labor.

Other and further objects and advantages of the invention will appear from the following description taken in connection with 35 the accompanying drawings, in which

Fig. 1 is an end elevation of a portion of a car showing the invention in position therein, with parts in section and parts broken away;

40 Fig. 2 is a view at right angles from that shown in Fig. 1, with parts in section and parts broken away;

Fig. 3 is a horizontal section on line 3-3 of Fig. 2;

45 Fig. 4 is a section on line 4-4 of Fig. 3, showing the brake staff in elevated position;

Fig. 5 is a vertical section taken at a right angle from that shown in Fig. 4; and

50 Fig. 6 is a vertical section similar to Fig. 4, but showing a modified form of the device.

In the use of hand brakes on flat cars and the like, it is frequently desirable that the 55 brake staffs be moved to a lowered position

to enable the car to be loaded as when logs, poles or other articles longer than the car are being transported. It is also desirable that the means for holding the staff in elevated position be automatic and certain in 60 its operation. In the form of the device selected to disclose the invention the brake staff is moved vertically to extended position and the latch is moved to latching position by gravity. 65

On the drawings, the reference character 5 designates a portion of one end of a railway car, comprising the end sill 6 above which is secured the floor 7 in the usual manner. A brake staff support or step 8 is rigidly secured to said sill. A sleeve or 70 sleeve member 12 is rotatably mounted in bearings 9 and 10 at the upper and lower portions of the step or support 8, respectively. The sleeve member 12 is provided with an axial bore angular in cross-section in which is telescopically mounted a brake staff 13. The brake staff is angular in cross-section whereby the same is free to slide longitudinally of the sleeve member 12, but is prevented from turning relative thereto. A wheel or lever 20 is mounted 75 on the upper end of the staff for operating the same.

In the type of brake in which the staff 85 is not geared to the winding drum, as in the present construction, the sleeve member 12 is employed as the winding drum. As shown, a short drum 14 having a spiral groove 15 is mounted on the lower end of 90 the sleeve 12. The drum 14 is considerably larger in diameter than the sleeve 12, whereby during the initial turning of the sleeve the slack is readily taken up in the brake operating cable 11 by said drum. 95

On further turning of the brake staff the cable will wind on the sleeve intermediately between the two bearings. This is considered an important feature of the invention because during the final application of 100 the brakes when considerable force is necessary the same is applied to the sleeve in such a manner that the pressure is substantially the same on the two bearings.

Suitable means are provided for holding 105 the brake staff in elevated position while the brakes are being applied. It is desirable that the means for this purpose be so constructed that when the staff is elevated the means will automatically engage the staff 110

and hold the same in elevated position. It is also desirable that this means engage beneath the end of the staff in order that the brake staff shall extend a minimum distance beneath the car when the staff is in lowered position. As shown, the sleeve 12 is provided with a pocket 16 at one side thereof. The pocket is provided with a slot 17, an inclined surface 18 forming a guide or slide-way, and a ledge or support 19. A brake staff holding or retaining member 21 is slidably mounted in the pocket.

The holding member 21 comprises a brake staff engaging member 22 having a body portion 23 for engaging the side of the brake staff for positioning the said member and for preventing its inward movement during operation, and a flange or support 24 for engaging beneath said staff for supporting the same. The support 24 is adapted to engage the ledge 19 when the brake is in elevated position. A handle 25 extending through the slot 17 is provided for elevating the brake staff engaging member. The slot 17 is arranged substantially parallel with the inclined surface 18 whereby the member 22 will slide by gravity down the inclined plane and the handle 25 will slide through the slot 17 when the brake staff is elevated above the holding member.

The brake staff 13 is provided with suitable means for preventing the withdrawal of the same when it is raised to operative position. As shown, the sleeve 12 is provided with oppositely arranged grooves 26 which extend upward from the bottom of the sleeve and terminate at 27 to form shoulders adjacent to the upper end of the pocket 16. The staff 13 is provided with laterally extending projections 30. These projections may be formed by the projecting ends of a pin or bolt extending through the lower end of said staff.

Suitable means are provided for holding the brake staff and drum in adjusted position. Any suitable means may be employed for this purpose. As shown, a bracket 28 is rigidly connected to the end of the car as to the end sill 6. A bearing 29 is journaled in the bracket and this bearing is provided with an angular axial opening through which the brake staff extends. A ratchet wheel 31 provided with an angular opening is slidably mounted on the brake staff 13 and is provided with crown teeth 32 which are adapted to be engaged by a pawl 33 pivotally mounted on suitable lugs carried by the bracket 28. A weight member 34 pivotally mounted on the pivot 35 of the pawl is adapted to hold the pawl in engagement with the teeth 32 when swung to the position shown in Fig. 1. The pivot 35 for the latch is adjacent to the outer end thereof whereby when the weight is turned 65 up out of contact therewith the pawl will

fall by gravity out of contact with the teeth 32 and permit the unwinding of the brake operating chain or cable. Since the specific features of this brake staff holding mechanism constitutes no part of the present invention it is not thought necessary to further illustrate or describe the same.

In the operation of the device, when it is desired to apply the brakes, the staff 13 is elevated until the projections 30 engage the shoulders 27 whereupon the brake staff holding member 21 will slide by gravity down the incline 18 into engagement with the ledge 19. The brake staff is now lowered until the lower end thereof seats on the flange or support 24, after which the brakes are applied by rotating the lever 20 in the usual manner.

When the brake staff is in elevated position, the holding member 22 is held from accidental movement outward by the inclined surface 18 and prevented from moving inward by the body portion 23 engaging the brake staff 13.

When it is desired to lower the brake staff the same is elevated along the incline sufficiently to permit the holding member 21 to be moved upwardly and outwardly out of the path of the brake staff, after which the latter is moved to lowered position. The handle 25 of the brake holding member 21 is preferably curved as at 36, whereby the same may be elevated by the foot of the brakeman when it is desired to lower the brake staff.

This type of brake staff is especially desirable on flat cars employed in transporting logs, poles, metallic structures and the like that are adapted to extend beyond the end or ends of the car. In loading, unloading and transporting long structures the brake staff, if it extends above the floor of the car, is in the way and is likely to be broken off or otherwise damaged. It is desirable therefore that the wheel be flush with or below the plane of the floor surface. This is accomplished by providing a curved recess 38 in the end of the car floor for receiving the wheel or lever 20. The upper surface of the wheel has no objectionable upwardly extending projecting parts. As shown, the upper surfaces of the hub and rim are substantially in a common plane.

Suitable means are provided for securing the wheel to the staff whereby when the same is lowered in the recess 38 no part extends above the same. As shown, the wheel is provided with a depending hub 39 having an angular socket 41 therein for receiving the upper end of the staff 13. The hub is secured to the staff 13 by a bolt 42 which extends through said staff and hub, the head 43 of said bolt being angular and seating in a corresponding opening 44 in one side of said hub. A nut 45 clamps the staff

against one side of the hub, the head 43 seating in the opening 44 assists materially in preventing the removal of the wheel. By means of this arrangement the hub is not only rigidly clamped to the staff but is held at opposite sides from being removed.

In assembling the mechanism, the holding member 21 is first inserted from the inside of the sleeve 12. The handle 25, which is straight, is made to extend through the opening 17 after which the outer end is bent downwardly as shown in Fig. 4. The staff 13 is inserted in the sleeve from beneath the same and the hand wheel 20 is then applied.

The modified form of the device shown in Fig. 6, differs from that described above in that the slot or opening 50 in the pocket 51 of the sleeve member 12 is made large enough to permit the insertion of the head 52 of the holding member 53 from the outside. After the holding member 53 is inserted in the pocket, a pin 54 is inserted transversely across the lower portion of the slot or opening 50 for preventing the removal of the holding member and for guiding the stem or handle 55 to cause the head 52 to slide down the incline surface 18 when the brake staff 13 is elevated.

The head 52 comprises a laterally extending portion or shoulder 56 which is adapted to engage the ledge or shoulder 19 and the bottom of the staff for supporting the same, and a vertical portion or stop 57 for engaging the side of the staff for limiting the inward movement of the holding member. The stem or handle 55 is similar to the corresponding element 25 described above, and like it extends upwardly and outwardly substantially parallel with the incline surface 18 whereby the holding member is free to move to holding position by a sliding movement only, when the staff is elevated above the same. The stem 55 is provided with an angular extension 58 as in the previously described construction, whereby the holding member may be raised to inoperative position by the hand or foot of the operator.

The operation of the device is substantially the same as that described above.

While we have disclosed the brake operating cable as being wound directly on the sleeve 12 it is understood that with a geared mechanism the cable will be wound on a

separate drum as is usual in such constructions. It is also understood that the winding mechanism may be operated in any position of the brake staff.

We claim as our invention:

1. In a drop brake mechanism, a sleeve having a non-circular opening extending therethrough, a brake staff slidably mounted in said opening, a latch slidably mounted in said sleeve and adapted to slide by gravity by a movement of pure translation into engagement with said staff for holding the same in elevated position, and a ledge for engaging the lower portion of said latch for holding the same in operative position to support said staff.

2. In combination, a rotating brake operating member, a rotated member for slidably receiving said operating member, said operating member being provided with a pocket having an inclined wall, a ledge extending inwardly from the lower portion of said wall, and a holding member mounted in said pocket and adapted to slide by gravity down said inclined wall onto said ledge for supporting said operating member when the same is raised to fully elevated position.

3. In a drop brake for railway cars, a rotated member provided with an inclined surface and with an inclined opening parallel with said surface, a ledge or shoulder beneath said inclined surface, a rotating member slidably mounted in said rotated member, a holding device adapted to slide down said surface into engagement with said ledge for engaging said rotating member for holding the same in elevated position, a handle on said device extending through said opening, and a foot engaging portion formed on the free end of said handle.

4. In a drop brake mechanism for railway cars, a rotatable sleeve member provided with a pocket in one wall thereof, said pocket being provided with a slot and with an inclined surface, a brake staff slidably mounted in said sleeve, a holding member slidably mounted on said incline surface and having a guiding stem extending through said slot, and a pin extending across said slot for retaining said member in said pocket.

In testimony whereof we affix our signatures.

CHARLES J. NASH.
JACK WILSON.
